UNITED STATES PATENT OFFICE.

JULIUS C. RUEDT, OF MILWAUKEE, WISCONSIN, ASSIGNOR TO PHOENIX HOSIERY CO., OF MILWAUKEE, WISCONSIN, A CORPORATION OF WISCONSIN.

HOSIERY AND METHOD OF MAKING THE SAME.

Application filed March 15, 1924. Serial No. 699,430.

To all whom it may concern:

Be it known that I, JULIUS C. RUEDT, a citizen of the United States, residing at Milwaukee, in the county of Milwaukee and State of Wisconsin, have invented a certain new and useful Improvement in Hosiery and Methods of Making the Same, of which the following is a full, clear, concise, and exact description, reference being had to the accompanying drawings, forming a part of this specification.

My invention relates to hosiery.

Among the primary objects of the invention may be enumerated the production of the complete equivalent of the full fashioned stocking at present in general use, without the use of the cumbersome and expensive flat bed machines for knitting the same.

Another object is to produce a blank for such a stocking in a single automatic operation, containing all the fabric necessary to form the finished article and no excess fabric beyond that necessarily allowed for seaming.

Further objects and advantages of the invention will become apparent as the description proceeds.

In the accompanying drawings:

Fig. 1 is a plan view of the finished blank as it comes from the machine, spread out flat except for the heel loops;

Fig. 2 is a similar view of the foot portion only after the heel loops have been cut;

Fig. 3 illustrates the third step of the process;

Fig. 4 illustrates the fourth step of sewing the sole and toe and the ends of the long heel flaps;

Fig. 5 illustrates the fifth operation of seaming the entire stocking;

Fig. 6 illustrates the sixth operation of rounding the heel;

Fig. 7 shows the finished stocking; and

Fig. 8 is a diagram of the needles in the needle cylinder.

In the production of a blank according to the invention, I begin at the toe with a minimum number of stitches, and add stitches progressively at irregular intervals to shape or fashion the blank, without at any time being under the necessity of dropping stitches or narrowing the blank. While knitting the heel strips, part of the

needles in the middle of the blank are held out of operation, but they retain their loops and continue knitting after the formation of the heel strips, so that this part of the blank is formed simply by making some of the wales of greater length than others, without narrowing of the fabric at any time. The result is a tapered blank, with selvaged edges throughout, both edges of the heel strips being selvaged, so that the finished blank can be freely handled without danger of raveling.

Referring first to Figs. 1 and 8, I set up the blank with the width from A to B, and knit a short tab 10 of constant width. Immediately thereafter I widen at a relatively rapid rate to points C—D, and subsequently at a slower rate to points E—F. Throughout this portion of the knitting I preferably employ two threads, a main thread, and a reinforcing or splicing thread to form a fabric of greater thickness than the main portion of the blank. I next proceed to form the foot portion, comprising an instep portion 12 of single thickness, and side portions 14 of extra weight, produced by taking two threads on the needles from E to G and from H to F. This continues up to point 16, at which point I widen by the addition of just a few more stitches at the edge of the fabric, ending the foot portion proper with fabric extending from I to J, with the reinforced extending from I to G and from H to J.

I now throw out of action all the needles except those between L and J, and on these alone, using two threads, I knit a loose course 17, a short flap 18, a single loose course 20, and a long flap 22. All the needles are now thrown into action once across, bringing the free end of strip 22 back and uniting it at L with the base of flap 18. On the return movement, all the needles from K to J are thrown out of action, leaving only those from I to K. I now knit a loose course 23, a short flap 24 duplicating flap 18, a single loose course 26 and a long flap 28 duplicating flap 22. It will be apparent that these flaps will have selvaged edges throughout.

All the needles are now thrown into action, and the back of the heel is formed. While a satisfactory article might be produced by using two threads in this portion of the blank on needles from E to G and from H

to F, I prefer to make the reinforce slightly wider, from I to M and J to N, as clearly indicated in the drawings. After knitting up to the level indicated at 30, I again change 5 the width of the reinforce from I to O and from P to J to form a narrow splice portion 32 on each edge of the blank. Above portion 32 I form the entire fabric with a single thread, and add stitches, a few at a time, 10 symmetrically on opposite sides of the blank, as at 34, 36 and 38, to produce a fashioned calf portion. I also prefer to widen the blank again slightly at 40 above the knee, to produce a better fitting article. The width 15 of the fabric after widening for the calf is indicated in Fig. 8 by the distance from Q to R, and at the top of the blank by the distance from S to T. The needles 41 are indicated only. In practice the actual number 20 of needles is much greater than shown on the drawing.

The blank above described may be readily produced on any one of several well known types of knitting machines provided with 25 suitable mechanism for adding needles and inserting the reinforcing thread, and set up with the necessary pattern chain and cam controls for automatically performing the operations above set forth. U. S. Patents 30 1,148,055, July 27, 1915, and 1,152,850, September 7, 1915, both issued to R. W. Scott, illustrate one type of machine suitable for this work. As those skilled in the art can readily set up the type of machine exemplified in the above patents, or some other type, 35 to produce the blank illustrated in Fig. 1, this specification has not been encumbered with the details of construction of a machine for knitting such a blank.

40 The next step in the process is indicated in Fig. 2, and comprises simply cutting the fabric along the loose courses 20 and 26 to separate flaps 18 and 24 from flaps 22 and 28.

45 The next step in the process is indicated in Fig. 3 and comprises seaming the selvaged inner edge of flap 22 across the end of flap 18, a good portion of flap 18 being cut off and thrown away in the process, substantially down to loose course 17.

50 The next step is indicated in Fig. 4, which is a bottom plan view of the foot portion. The ends of flaps 22 and 28 have been seamed together at 42 to close the heel pocket, and the toe pocket has also been 55 formed in the usual way by turning in the fabric at the end and seaming at 44. It will be noted that all the fabric seen in Fig. 4 is reinforced, the sole of the foot being formed by the reinforced portions 14.

60 The next step is to seam the entire blank as shown in Fig. 5, beginning at 46 and running past the heel and up the selvaged edges at the back to the top of the blank. This is followed in Fig. 6 by rounding off and trimming the heel pocket at 48, after which the

blank is dyed and boarded to produce the finished stocking of Fig. 7. The hem at the top is preferably sewed as part of the operation performed at the time the entire blank is seamed, as shown in Fig. 5. 70

It will be apparent that in the finished stocking all the wales of the leg portion run parallel to the front edge of the stocking when folded flat, as in Fig. 7, that the blank can readily be produced by entirely automatic operation, and that all portions thereof, including the strips necessary for forming the heel pocket, have selvaged edges throughout, so that the blank can be freely handled without fear of raveling the same. In appearance and accuracy of fit, the product is fully equal to that produced at present on the Cotton type of machine, and as the individual loops have not been pulled and stretched by transfer points, in narrowing the fabric, it is better than the product of the Cotton machine with respect to strength and serviceability. 80

Without further elaboration, the foregoing will so fully explain the gist of my invention, that others may, by applying current knowledge, readily adapt the same for use under various conditions of service, without eliminating certain features which may properly be said to constitute the essential items of novelty involved, which items are intended to be defined and secured to me by the following claims. 90

I claim:

1. The method of knitting a stocking blank which comprises setting up the fabric as a narrow toe strip, widening at appropriate places to form a fashioned toe and foot portion, reinforcing the toe and the sides of the foot portion with an additional thread, interrupting all but a few needles at one side and knitting a narrow strip, uniting the end of said strip with the body to form a fabric loop by knitting clear across, interrupting all but a few needles at the other side and knitting another narrow strip, uniting the end of said strip with the body by knitting clear across, reinforcing both strips throughout, knitting the ankle, calf and leg portions, and reinforcing the outer edges of the ankle portion part way up. 100

2. The method of making a stocking which comprises forming a fashioned blank with selvaged edges in which all the wales run parallel to the center line of the blank and widening occurs by adding wales at the edges of the blank, forming two loops of extra length fabric in the edges of the blank at the heel portion, cutting each loop into a short portion coming up from the foot and a long portion coming down from the ankle, sewing the end of each short portion to the side of the adjacent long portion, sewing the ends of the long portions together, turning in the edges of the blank at the toe and 110

115

120

125

130

sewing across the end of the toe, sewing the edges of the blank together, and rounding off the heel corner.

3. The method of making a stocking which comprises forming a fashioned blank with selvaged edges in which all the wales run parallel to the center line of the blank and widening occurs by adding wales at the edges of the blank, forming two loops of extra length fabric in the edges of the blank at the heel portion, cutting each loop into a short portion coming up from the foot and a long portion coming down from the ankle, and sewing the end of each short portion to the sides of the adjacent long portion to form the heel pocket.

4. A one piece blank shaped for forming a complete full fashioned stocking having the extra fabric for forming the heel pocket provided in the form of strips of extra fabric in the edge portions of the blank, the ends of said strips being continuous with wales of the body, the body between said edge portions being continuous, whereby said strips are doubled into loops, the toe, the edges of the foot portion, the loops and the edges of the ankle portion being reinforced with extra thread to form a reinforced toe, foot bottom, heel and heel splice in the finished stocking, said reinforcement being of predetermined different widths in

each of the different portions, one course in each loop being knit loose to define a cutting line dividing the loop into a short flap coming up from the foot and a long flap coming down from the ankle.

5. A one piece blank shaped for forming a complete full fashioned stocking having the extra fabric for forming the heel pocket provided in the form of strips of extra fabric in the edge portions of the blank, the ends of said strips being continuous with wales of the body, the body between said edge portions being continuous, whereby said strips are doubled into loops, one course in each loop being knit loose to define a cutting line dividing the loop into a short flap coming up from the foot and a long flap coming down from the ankle.

6. A one piece blank shaped for forming a complete full fashioned stocking having the extra fabric for forming the heel pocket provided in the form of strips of extra fabric in the edge portions of the blank, one course in each strip being knit loose to define a cutting line dividing the strip into a short flap coming up from the foot and a long flap coming down from the ankle.

In witness whereof, I hereunto subscribe my name this 11th day of March, 1924.

JULIUS C. RUEDT.
